ATTORNEY.

UNITED STATES PATENT OFFICE

SHELIDA P. STARK, OF OTTOSEN, IOWA

OPERATING MECHANISM FOR BOX-CAR DOORS

Application filed July 3, 1926, Serial No. 120,371. Renewed August 3, 1929.

The present invention relates to box cars, and the more particular reference to a device for assisting in the operation of the sliding doors of such cars.

It is well known that frequently it is practically impossible to open or close the sliding doors of box cars, particularly when loaded with grain and the like owing to the sagging of the car body and to the warping and dis-
10 alinement of the hanger and guide rails.

While these defects cannot be overcome to any appreciable extent, the present invention has for an object to provide a device which may be coupled between the car body and the
15 door for forcing the latter to move, the device being manually operable.

Another object is to provide a door moving device for box cars which may be quickly and easily folded up into compact form and may
20 be easily carried from car to car; and a device which may be readily opened out and applied in proper position.

A further object of the invention is to provide a device of this character with two parts:
25 a door engaging part, and a car body engaging part, both parts being constructed so that they may be independently applied to their respective parts and will remain in position to permit the application, operation and re-
30 moval and folding of the device all by one man.

With the foregoing and other objects in view, the invention will be more fully described hereinafter, and will be more particularly pointed out in the claims appended hereto.

In the drawings, wherein like symbols refer to like or corresponding parts throughout the several views.

40 Figure 1 is a side elevation of a box car with the sliding door open and having the device of this invention applied thereto for closing the door.

Figure 2 is a horizontal section through Figure 1 taken near the top thereof and looking down upon the door moving device.

Figure 3 is a detail side elevation of the door engaging section detached and folded, and

45 Figure 4 is a detail inner side elevation of

the car body engaging section, showing the rope or cable in position therein.

Referring to the drawings, Figures 1 and 2 show a box car body 10 having a side opening 11 closed by a door 12. The door is suspended by hangers 13 from a top rail 14 secured along the outer side of the body 10, and a bottom rail 15 also secured along the outer side of the car body and with which lugs 16 on the lower end of the door 12 engage to hold the
55 lower end of the door close to the side of the car body. The car body 10 also has the usual post 17 at the far side of the door opening 11 serving as a stop for the door 12 when closed.

The door engaging member comprises three claws 18, 19 and 20, the claws 18 and 19 being spaced one above the other and interbraced by a rod 21. The claws 18 and 19 are in the form of angle irons adapted to engage about the edge of the door 12, and
60 the rod 21 has its ends secured to the outer sides of the angle irons and is arched outwardly from the same to freely receive therebeneath the stop 22 of the car body. The other claw 20 is yieldingly connected to the first two claws 18 and 19, and is also so connected that the claw 20 may be collapsed toward the rod 21. Each claw 18 and 19 has pivotally connected to it a pair of hinged links 23 which are pivoted at their other ends to the diverging arms 24 of a pulley block 25 in which a pulley 26 is mounted. The block 25 has a third arm 27 to which a spring frame 28 is pivoted. A rod 29 is slidably mounted in the frame 28 and carries a spring 30 which engages at one end against the frame 28 and at its other end against a collar 31 on the inner end of the rod 29. The outer end of the rod 29 carries the
75 claw 20 which is adapted to engage about the outer edge of the door 12. The spring 30 is of sufficient strength to bind the claws 18 and 19 and 20 against the opposite ends of the door 12 and hold the pulley block 25 to the
80 door.

As shown in Figure 3 the door attaching member may be collapsed or folded into compact form by folding one of the pairs of links 22 upon each other to bring the opposite pair of links close to and substantially
85 90 95 100

parallel with the rod 21. The spring frame 28 may be swung over against the outer pair of links 22 as shown, and the section may thus be conveniently carried or packed away in a small space.

The second section, or the section which may be attached to the car body comprises a frame having three vertically spaced apart claws 32, 33 and 34 the inturned fingers of which are adapted to engage the inner edge of the post 17 as shown in Figure 1. The claws 32, 33 and 34 extend across the outer face of the post 17 and beyond the same and are connected together at their inner ends by an inwardly extending flange 35. Thumb screws 36 are threaded through the flange 35, and have swivelled heads 37 arranged opposite to the inturned fingers of the claws. The flange 35 between the upper claws 32 and 33 is arched or offset laterally away from the post 17 to accommodate any fixtures which may be carried upon the car body 10. The second frame thus constructed is adapted to carry a windlass 38 mounted on a shaft 39 journalled at one end in the upper claw 32 and supported at its other end in a bracket arm 40 carried by the frame and spaced outwardly from the upper claw 32. The shaft 39 has a crank handle 41 at the outer side of the bracket arm 40 by means of which the windlass 38 may be turned for winding thereon one end of a rope or cable 42.

The cable 42 passes from the drum 38 over the pulley 26 and is returned from the under side thereof to an idler pulley 43 which is mounted upon the intermediate claw 33, the latter having spaced from its outer side a bracket arm 44 which engages across the outer side of the idler 43 to support the pivot thereof. The cable 42 after passing downwardly from the idler 43 is secured to the lower claw 34 upon which the cable is anchored.

In use, the door engaging member is unfolded by merely straightening out the pairs of links 23 as shown in Figure 1 and swinging the spring frame 28 out into line with the pulley block 25. The claw 20 is now pulled away from the claws 18 and 19 and the claws are engaged about the outer and inner edges of the door 12. As soon as the claws are released, the spring 30 is permitted to act for drawing the rod 29 inwardly and binding the claws against the opposite edges of the door 12. The spring 30 therefore holds the door engaging member in position without tensioning the cable 42 or without any manual assistance. The car body engaging member is now applied to the post 17 or the like of the car body 10. The inwardly extending fingers of the claws 32, 33 and 34 are engaged about the inner edge of the post 17 while the thumb screws 36 are advanced through the flange 35 to engage the swivel heads 37 against the outer edge of the post

17. This binds the car body engaging member in position. The rope or cable 42 may now be threaded over the various pulleys as shown in Figure 1 and the windlass 38 operated to draw the cable taut.

As the handle 41 is turned it contracts the cable 42 and draws the door engaging member forwardly, carrying with it the door. When considerable leverage is obtained through the crank or handle 41 which may be made of the desired radius as compared with the drum 38, and the pulley 26 in the door engaging member, so that relatively light pressure only need be applied to the handle 41 for forcing the door 12 to move upon its rails 14 and 15, even though the rails sag or otherwise become distorted.

It is readily apparent that the device may be operated by one man as each member is independently applied to its respective part of the car and the device may be operated by the single handle 41. It is also apparent that the separate parts remain in position when once placed upon the car body and car door so that their position does not depend upon a relative tension between the parts.

It will be noted from Figures 1 and 4 that the cable 42 extends downwardly from the idler 43 and through the space between the flange 35 and the post 17. This portion of the cable 42 in this space may be grasped by hand for manual and direct manipulation and for facilitating the taking up or tying of the cable 42 to the lower claw 34. To further reinforce and strengthen the car body engaging drum, the same may be provided with one or more vertical braces 45 which extend between the pivots of the lower pulley 43 and the drum 38.

I do not wish to be restricted to the size, form, and proportions of the various parts, and obviously changes could be made in the construction herein described without departing from the spirit of the invention, it being only necessary that such changes fall within the scope of the appended claims.

What is claimed is:—

1. A detachable device for opening sliding car doors comprising a clamping member adapted for engagement with a car door and having a pulley thereon, a car body engaging member adapted to be clamped upon the car body in a position adjacent the door, a windlass on said body engaging member, and a rope secured at one end to the body engaging member and connected to the windlass at its other end, the intermediate portion of said rope being adapted to pass over said pulley on the door engaging member.

2. A detachable device for opening sliding car doors comprising a clamping member having spring operating claws for engagement against opposite edges of the door and including a pulley arranged at the outer

side of the door, a cable trained over said pulley, a car body engaging member adapted to be secured to the car at a point remote from said door, one end of said cable being adapted for connection with said car body engaging member, and a winding drum carried upon the car body engaging member and having the opposite end of said cable secured thereto, whereby upon the winding of said drum said cable is contracted and caused to move over said pulley of the door engaging member for advancing the same.

5. A detachable device for opening sliding car doors comprising a pair of clamping members, one member being adapted for clamping engagement upon a car door and the other member being adapted for clamping engagement upon the car body at a point opposite to the door, and leverage means 10 connecting said members together for operation to relatively move the members and move said door.

6. A detachable device for opening sliding car doors comprising a pair of claws, a brace rod connecting said claws together for engagement against the inner end of a car door, a third claw for engagement against the outer end of the car door, a pulley block connected to said third claw, pairs 15 of foldable links connecting the pulley block to said first pair of claws, a spring interposed between the pulley block and said third claw for yieldingly pointing the claw against the inner and outer edges of the door, a pulley in said pulley block, a cable trained over said pulley, a frame adapted for engagement with the car body opposite to said door, means for clamping said frame upon the car body, one end of said cable being secured to said frame, and a windlass in the frame connected to the opposite end of 20 said cable and adapted to be operated for winding the cable thereon and effecting the relative movements of the door and car body 25 engaging members.

7. A detachable device for opening sliding car doors comprising a windlass including a frame and a cable winding shaft, a cable attached at one end to the windlass 30 frame, and at its opposite end to said winding shaft, a clamp adapted for detachable engagement with the door stop bar of the box car, a flexible connection between the clamp and said windlass, and additional 35 clamps adapted for detachable engagement over the edge of the door remote from the door stop bar, said additional clamps being operatively connected to said cable.

In testimony whereof, I have affixed my
80 signature.
